UNITED STATES PATENT OFFICE.

HERBERT WENSTROM GUETTLER, OF CHICAGO, ILLINOIS, ASSIGNOR TO AMERICAN BARKING DRUM COMPANY, OF CHICAGO, ILLINOIS, A CORPORATION OF ILLINOIS.

BARKING-DRUM.

1,311,225.

Specification of Letters Patent. Patented July 29, 1919.

Application filed June 6, 1918. Serial No. 238,430.

To all whom it may concern:

Be it known that I, HERBERT WENSTROM GUETTLER, a subject of the King of Norway, residing at Chicago, in the county of Cook, 5 State of Illinois, have invented certain new and useful Improvements in Barking-Drums; and I do hereby declare the following to be a full, clear, and exact description of the invention, such as will enable others 10 skilled in the art to which it appertains to make and use the same.

The present invention relates to bark removing machines of the type wherein blocks of wood, from which the bark is to be removed, are tumbled in a rotating drum. 15 The improvements comprising the invention reside in the provision, within the drum, of devices of such a character as to insure tumbling of the wood, as opposed to a mere 20 sliding movement, and, at the same time, to effectively prevent brooming or similar injury which is liable to occur when tumbling devices of the usual form are employed.

According to the invention, as preferably 25 carried into practice, the drum comprises a plurality of angle bars which extend from end to end thereof and have their flights directed inwardly toward the longitudinal axis of the drum so as to form the aforementioned tumbling devices. These bars are arranged in pairs. With their said 30 flights positioned opposite and in proximity to each other and in parallel relation, the pairs of flights being disclosed sufficiently 35 far apart from one another to provide an interrupted or pocketed, instead of a practically smooth, interior surface, and each pair of flights being connected by a guard or cover of U-section, which straddles them 40 and, hence, is likewise disposed with its rounded base directed toward the drum axis. Consequently, when the drum is in motion and the tumbling of the wood takes place, the latter action will occasion no injury to 45 the wood by reason of the fact that the ends of the blocks will strike against the rounded guards, instead of against the sharp edges of the flights of the angle bars as would otherwise be the case.

50 An embodiment of the invention is illus-

trated in the accompanying drawing, wherein:

Figure 1 is a side elevation of a barking drum equipped with the present improvements;

55

Fig. 2 is a transverse section thereof; and

Fig. 3 is an enlarged, fragmental perspective view of some of the pairs of angle iron bars and the associated guards.

Referring more particularly to said drawing, the improved drum, generally designated 5, is preferably cylindrical in shape, as shown, and comprises a plurality of angle iron hoops 6, arranged at suitable intervals apart and connected together by bars 7, likewise of angle iron form, which extend from end to end of the drum and, in conjunction with the subsequently-described guards, constitute the tumbling devices. These bars 7 are disposed in pairs, with their flights directed inwardly toward the longitudinal axis of the drum, the free longitudinal edges of the bases of the adjacent pairs of bars being spaced apart so as to provide slots 8 through which the detached pieces of bark 75 may be discharged from the drum into the tank or the like (not shown) wherein the drum is mounted. The flights of each pair of bars face each other, and are positioned in comparatively-close, parallel relation, but the 80 pairs of flights themselves are disposed an appreciable distance apart from one another in order to provide an interrupted, instead of a practically smooth, interior surface, as previously stated, thereby insuring the 85 positive tumbling of the blocks. The interruptions thus formed are in the nature of longitudinal pockets which are sufficiently wide to enable them to catch the corners of the blocks therein during the rotation of 90 the drum, whereby the blocks are positively forced to travel part way around with the drum. The slots 8 extend centrally along the bottoms of the pockets.

The drum is supported by means of devices which alternate with the hoops 6 and are here shown as comprising pairs of angle iron hoops 9 arranged with their flights 95 projecting outwardly from the drum and disposed opposite and in close proximity 100

to each other to receive between them solid rings 10, the latter and the flights of the hoops being riveted together, while the bases of the hoops are secured in like manner to the bases of the angle bars 7. The rings 10 may rest upon or otherwise engage rollers or other supports of any desired character, illustration of this feature being omitted as not involved in the actual invention.

5 10 Rotation of the drum may likewise be effected in any suitable manner; for instance, by providing at the center of the drum a sprocket ring 11 which encircles said drum and is designed for engagement with driv-

15 ing gearing (not shown) which, in turn, is driven from a suitable source of power, the said sprocket ring being mounted between the out-turned flights of a pair of angle iron hoops 12.

20 20 The devices for tumbling the blocks of wood comprise the pairs of angle iron bars 7 and their associated guards, as previously stated. The latter, which are indicated at 13, are in the form of U-shaped or trough-

25 like members which straddle the flights of the bars and have their legs projecting across the outer faces thereof, the flights and guards being co-extensive in length and fastened together at intervals by rivets 14,

30 30 the central portions of which pass through spacing sleeves 15 disposed between the flights. The rounded bases of the guards are likewise directed toward the axis of the drum, as will be understood; and since the

35 35 guards fit over the pairs of flights, the effect produced is that of utilizing tumbling devices having closed or solid edge faces which are rounded along their edges.

The spacing of the tumbling devices insures their effecting the necessary tumbling action, as above explained, as distinguished from a mere sliding movement of the blocks; but instead of the ends of the blocks striking against the sharp edges of the flights

40 40 of the angle bars during their tumbling movements and being split or broomed thereby, they will hit only the rounded bases of the guards and will be uninjured in consequence. Further description of the invention, its mode of operation, and its advantages, is deemed unnecessary in view of the foregoing, and is, accordingly, omitted; but it may be stated that while the preferred embodiment of the invention is disclosed herein, no limitation to the precise structural details of such disclosure is intended, since modifications and changes with relation to the improved tumbling devices may well be made within the scope of the invention as claimed and the said devices may be used in other and different types of drums.

I claim as my invention:

1. In a barking apparatus, a hollow, rotatable container for the blocks, having a plurality of tumbling devices of substantially

U-section, the rounded bases of which are directed inwardly toward the center of the container; said devices being spaced apart an appreciable distance from one another so as to form pockets between them adapted to 70 catch the corners of the blocks therein during the rotation of the container and thereby positively force said blocks to travel partway around with said container.

2. In a barking apparatus, a rotatable 75 drum to contain the blocks, provided with a plurality of interiorly-located, longitudinally-arranged tumbling devices having rounded edge faces, said devices projecting toward the axis of the drum in substantially parallel relation to one another and being spaced apart an appreciable distance so as to form longitudinal pockets between them adapted to catch the corners of the blocks 80 therein during the rotation of the drum and thereby positively force said blocks to travel 85 partway around with said drum.

3. In a barking apparatus, a hollow-rotatable container for the blocks, having a plurality of longitudinally-arranged tumbling 90 devices, which are spaced apart an appreciable distance from one another so as to provide an interrupted tumbling surface within the container, each tumbling device comprising a pair of angle bars, 95 which are directed inwardly of the container and are disposed in spaced, parallel relation, and a U-shaped guard straddling said flights and fastened thereto.

4. In a barking apparatus, a hollow, rotatable container for the blocks, having secured within it a plurality of longitudinally-arranged tumbling devices, which are spaced apart an appreciable distance from one another so as to provide an interrupted tumbling 105 surface within the container, each tumbling device comprising a pair of angle bars, the flights of which are directed inwardly of the container and are disposed in spaced, parallel relation, and protecting means attached 110 to each tumbling device for preventing the blocks from striking against the edges of said flights.

5. In a barking apparatus, a hollow rotatable container for the blocks, having secured 115 within it a plurality of longitudinally-arranged tumbling devices, which are spaced apart an appreciable distance from one another so as to provide an interrupted tumbling surface within the container, each tumbling device comprising a pair of angle bars, 120 the flights of which are directed inwardly of the container and are disposed in spaced, parallel relation, and protecting means attached to each tumbling device and bridging the 125 space between the flights thereof for preventing the blocks from striking against the edges of said flights.

6. In a barking apparatus, a rotatable, cylindrical container for the blocks, having a 130

plurality of longitudinally-arranged tumbling devices of substantially U-section, the rounded bases of which are directed inwardly toward the axis of the container; said devices being spaced apart an appreciable distance from one another, so as to form longitudinal pockets between them adapted to catch the corners of the blocks therein during

the rotation of the container and thereby positively force said blocks to travel partway 10 around with said container, said pockets having their bottom walls provided with longitudinal bark-discharging slots which are disposed medially thereof.

In testimony whereof I affix my signature. 15
HERBERT WENSTROM QUETTLER.
